Lloyd C. Norman

BY *George Webster* ATTORNEY

UNITED STATES PATENT OFFICE.

EDWARD A. GRAY AND LLOYD C. NORMAN, OF STOCKTON, CALIFORNIA.

ANIMATED ADVERTISING DEVICE FOR MOVING VEHICLES.

1,359,984.

Specification of Letters Patent.

Patented Nov. 23, 1920.

Application filed February 17, 1920. Serial No. 359,320.

To all whom it may concern:

Be it known that we, EDWARD A. GRAY and LLOYD C. NORMAN, citizens of the United States, residing at Stockton, in the county 5 of San Joaquin, State of California, have invented certain new and useful Improvements in Animated Advertising Devices for Moving Vehicles; and we do declare the following to be a full, clear, and exact description of the same, reference being had to the accompanying drawings, and to the characters of reference marked thereon, which form a part of this application.

This invention relates to improvements in 15 animated advertising devices, and particularly to a type adapted to be placed on moving vehicles of all kinds which are used for passengers, and also on ferry-boats and similar vessels.

20 The principal object of the invention is to provide a device, arranged in combination with an advertising card, poster, or other medium, which will cause the eye to be attracted thereto and arrest the attention 25 of the beholder with any change of speed or movement of the vehicle, etc., in which the device is mounted.

Another object is to provide such a device 30 which is automatic in its action with said change of speed, and is a complete unit itself. That is, it is not dependent on any outside force such as electricity or other power, for its actuation, and hence when once installed, is no longer a source of expense to the proprietor or the advertiser.

35 A further object of the invention is to produce a simple and inexpensive device, and yet one which will be exceedingly effective for the purposes for which it is designed.

40 These objects we accomplish by means of such structure and relative arrangement of parts as will fully appear by a perusal of the following specification and claims.

45 In the drawings similar characters of reference indicate corresponding parts in the several views.

50 Figure 1 is a front elevation of a card adapted to receive advertising matter thereon, and showing the outline of a human face, the eyeballs of which are arranged to move or show animation.

55 Fig. 2 is a detached front elevation of the actuating mechanism of the eyeballs.

55 Fig. 3 is a fragmentary end view showing

the mounting of an advertising card provided with our improved animating feature, in the usual display rack provided in trains, street-cars and the like.

Fig. 4 is a fragmentary rear perspective 60 partly broken out, of the actuating mechanism.

Fig. 5 is a top plan view of the movable member having the eyeballs painted thereon.

Referring now more particularly to the 65 characters of reference on the drawings, the numeral 1 denotes a substantially stiff card or poster adapted to receive advertising matter printed or otherwise impressed thereon.

70 Preferably at one end, the likeness of a human face 2 is impressed on the card, said face having the eye-slots 3 cut out through the card.

75 Our invention resides in the provision of automatically actuated means for making it appear that said face is animated, in other words, the eyeballs are caused to move back and forth in the eye-slots with a change of speed or relative direction of movement 80 of the vehicle in which the card is mounted, so that it presents the same appearance as a living person looking from side to side.

85 This means consists of a pair of rigid members 4 preferably of wood, suitably spaced apart and positioned vertically of the card 1, being secured to the back thereof by gluing or some similar method.

90 Spaced apart vertically and extending between the members 4 are a pair of metallic tubes 5 provided with slots 6 running lengthwise thereof and facing each other in a vertical plane.

95 Positioned between the tubes is a strip 7 of metal or any suitable material having the representation of eyeballs 8 painted or otherwise impressed thereon, the spacing of these eyeballs being the same as that of the eye-slots 3. This member is positioned close to the back of the card 1, yet not so that it 100 will rub thereagainst.

Secured to the strip 7, or formed integral therewith as may be desired, is a metal piece 9 having spaced lugs 10 on both top and bottom, projecting into the slots 6, the lower 105 ones of such lugs preferably resting on the bottom of the lower tubes.

110 Positioned in the tubes are steel balls 11, polished and perfectly round so that they will roll very easily, these balls being be-

tween each pair of lugs 10, which are so spaced that the balls will have a certain freedom of movement therebetween.

When the balls roll, they of course carry 5 the member 9 with them, and their travel is only limited by the length of the slots 10.

In order to be able to adjust this length of travel so as to adapt the device for any spacing of the eye-slots 3 and make one size 10 and style of device universal for all conditions, the end members 4 are provided with plugs or stops 12 adapted to fit snugly into the tubes 5 to an extent such that when the end members are close against the tubes, the 15 member 9 will have a movement which will be the least ever required.

Then by drawing the members 4 apart, the movement permitted the member 9 is increased. This adjustment is of course effected before the pieces 4 are secured to the 20 card.

It will also be evident that inasmuch as the tubes are not fixed on to the plugs; and besides are circular, they may be rotated on the plugs, thus moving the slots therein nearer or farther from the card as the case may be, and likewise regulating the distance the strip 7 will be from the card. This is an essential feature, since the curvature of 30 car-roofs vary, and if the slots were in a fixed position, in one case the strips would rub against the card (when the curvature of the latter is excessive) or else would be so far away as to give a sunken appearance to 35 the eyes which would be undesirable. The most important thing however, is to prevent the strip from rubbing against the card, since this would increase friction to a point where the responsiveness of the strip to the 40 movement of the vehicle would be retarded, and it would necessitate the use of heavy balls to move the same, which would mean a thick and cumbersome device.

The actuating device may be made so 45 small and give good results, that the card to which it is attached may readily be placed in the usual holding rack 13 of a street car or other vehicle.

The tubes 5 are to be positioned perfectly 50 horizontal, when it will be apparent that any sudden relative change of speed of the vehicle, such as when starting, throwing off the power, and speeding up jerkily such as is almost invariably done on street cars, 55 will result in a movement of the balls in the opposite direction, thus causing the piece 7 having the eyeballs 8 impressed thereon, to move back and forth as the case may be, across the eye slots 3, giving the impression 60 of animation to the face, and drawing people's attention thereto and to the advertisement accompanying it.

In selling this device to the trade, we 65 would probably supply a master card of the desired size, together with a number of dif-

ferent faces having their eyes cut out, and adapted to be pasted over the original face from time to time, so as to relieve the monotony of a single face all the time, and thus freshen up the advertisement displayed 70 without actually changing it in any way.

While it is probable that we shall use a human or animal face, since this is most readily adaptable for the purpose, we do not wish to limit ourselves to such since various 75 other features expressing animation may be actuated in the same way.

From the foregoing description it will be readily seen that we have produced such a device as substantially fulfills the object of 80 the invention as set forth herein.

While this specification sets forth in detail the present and preferred construction of the device still in practice such deviations from such detail may be resorted to as do 85 not form a departure from the spirit of the invention, as defined by the appended claims.

Having thus described my invention what 90 we claim as new and useful and desire to secure by Letters Patent is:—

1. An animated advertising device for 95 moving vehicles comprising in combination with a card carrying advertising matter and having the likeness of the face of a living being impressed thereon, the eye-slots being cut out through the card, a strip behind and adjacent the eye-slots having the representation of eyeballs thereon spaced proportionately to the slots, horizontal tubes supporting the strip and positioned equally above and below the same, the latter being slidable 100 therein for relative and limited horizontal movement, balls in the tubes adapted to engage the strip and move the same in either direction, and means for adjustably limiting the extent of such movement.

2. An animated advertising device for 110 moving vehicles comprising in combination with a card carrying advertising matter and having the likeness of the face of a living being impressed thereon, the eye-slots being cut out through the card, a strip behind and adjacent the eye-slots having the representation of eyeballs thereon spaced proportionately to the slots, vertical lugs fixed on top and bottom of said strip, horizontal tubes mounted on the card and provided with horizontal slots through which the lugs pass 115 and which guide the same, the strip being arranged for automatic horizontal movement relative to the tubes, and means whereby the tubes may be turned to alter the lateral position of the slots therein, whereby the spacing of the strip from the card 120 may be adjusted.

3. An animated advertising device for 125 moving vehicles comprising in combination with a card carrying advertising matter and having the likeness of the face of a living 130

being impressed thereon, the eye-slots being cut out through the card, a strip behind and adjacent the eye-slots having the representation of eyeballs thereon spaced proportionately to the slots, vertical lugs fixed on top and bottom of said strip, horizontal tubes mounted on the card and provided with horizontal slots through which the lugs pass and which guide the same, the strip being arranged for automatic horizontal movement relative to the tubes, and plugs fixed to the card at each end of the tubes, the latter being turnably mounted thereon.

4. An animated advertising device for moving vehicles comprising in combination with a card carrying advertising matter and having the likeness of the face of a living being impressed thereon, the eye-slots being cut out through the card, a strip behind and adjacent the eye-slots having the representation of eyeballs thereon spaced proportionately to the slots, vertical lugs fixed on top and bottom of said strip, horizontal tubes on the card and provided with horizontal

slots through which the lugs pass and which 25 guide the same, and balls in both tubes adapted to bear simultaneously against the upper and lower lugs to move the strip with a tilting movement of the card.

5. An animated advertising device for 30 moving vehicles comprising in combination with a card carrying advertising matter and having the likeness of the face of a living being impressed thereon, the eye-slots being cut out through the card, a strip behind and 35 adjacent the eye-slots having the representation of eyeballs thereon spaced proportionately to the slots, and means whereby the strip will be held in parallel and adjustable spaced relation relative to the card irrespec- 40 tive of the angle of setting of the card, while allowing the strip freedom of horizontal movement relative thereto.

In testimony whereof we affix our signatures.

EDWARD A. GRAY.
LLOYD C. NORMAN.
